CONTROLLING DEVICE

William A. Smith, Sr., Athens, Pa., assignor to
Ingersoll-Rand Company, Jersey City, N. J., a
corporation of New Jersey

Application September 26, 1934, Serial No. 745,511

5 Claims. (Cl. 121—28)

This invention relates to fluid actuated rock drills, and more particularly to a controlling device adapted to control the action of the pressure fluid distributing element of the rock drill.

One object of the invention is to enable the movement of the pressure fluid distributing valve mechanism to be selectively accelerated or decelerated in order to cause the various elements or trains of elements of the rock drill to function in a manner best suited to produce maximum drilling results.

Another object is to maintain the consumption of pressure fluid to a minimum.

Other objects will be in part obvious and in part pointed out hereinafter.

In the drawing accompanying this specification and in which similar reference numerals refer to similar parts,

Figure 1 is a longitudinal elevation, in section, of a rock drill equipped with a controlling device constructed in accordance with the practice of the invention, and

Figures 2 and 3 are transverse views taken through Figure 1 on the lines 2—2 and 3—3, respectively.

Referring to the drawing, 20 designates, in general, a rock drill comprising a cylinder 21 having a piston chamber 22 to accommodate a reciprocating hammer piston 23. The cylinder 21 is provided with the usual back head 24 which may be secured to the cylinder in any suitable and well known manner.

Intermediate the ends of the piston chamber 22 is a free exhaust port 25 which is controlled by the piston 23 and a closure is provided for the front end of the piston chamber by a washer 26, the bore of which serves as a guide for a stem 27 of the piston.

In the portion of the cylinder lying rearwardly of the piston chamber 22 is an enlarged bore 28 containing valve mechanism 29 and rotation mechanism 30. The valve mechanism lies adjacent the rear end of the piston chamber 22 and is seated upon a plate 31 which serves as a closure for the rear end of the piston chamber.

The form of valve mechanism 29 selected for the purpose of illustration comprises a valve chest 32 which rests upon the plate 31 and is bored to provide front and rear valve chambers 33 and 34. The valve chambers which may be identical in all essential respects are in communication with each other at their inner ends through channels 35 defined by an intermediate interior portion of the valve chest and a bush-

ing 36 extending therethrough and which is seated with its front end in the plate 31 and extends with its rear end into a plate 37 interposed between the valve chest 32 and the rotation mechanism 30.

The pressure fluid employed for actuating the piston 23 is distributed to the ends of the piston chamber by valves 38 and 39 disposed in the valve chambers 33 and 34, respectively. Such pressure fluid is supplied to the valve chambers by a supply passage or passages 40 in the valve chest 32, rotation mechanism 30 and the back head 24. The supply passage 40 is in constant communication with the channels 35 and registers with a port 41 in the wall of the throttle valve 42 in the back head 24.

The throttle valve 42 may be of the rotary type having a central chamber 43 in constant communication with pressure fluid supply, so that when the throttle valve is rotated to bring the port 41 into registry with the supply passage 40 pressure fluid flows to the valve chambers to be distributed by the valves 38 and 39.

In the arrangement disclosed the supply of pressure fluid for the rear end of the piston chamber 22 is controlled by the valve 38. The pressure fluid flows from the adjacent channel 35 to the piston chamber through a rear inlet passage 44. Similarly, the valve 39 controls communication between the rear channel 35 and a front inlet passage 45 which extends through the valve chest 32 and the cylinder 21 to the front end of the piston chamber 22.

The valves 38 and 39 are shown as being identical and are, therefore, interchangeable so that in reassembling the valve mechanism either valve may be placed in either valve chamber without in any way impairing or varying the action of the rock drill. The valves are in the form of sleeves journalled on the bushing 36 and carry peripheral flanges 46 of which the outermost surfaces constitute actuating areas 47. The confronting ends of the valves also serve as actuating surfaces 48 and are constantly exposed to pressure fluid tending to throw the valves to their open positions.

The actuating areas 47 are exposed intermittently to pressure fluid and the supply of pressure fluid thereto is controlled by the piston 23. To this end the drill is provided with tripper passages 49 and 50 into which pressure fluid is constantly supplied by leak ports 51 leading from a source of pressure fluid supply, as for instance, from the supply passages 40. The tripper passage 49 opens into the piston chamber 22 at a point forwardly

of the free exhaust port 25 and has a branch passage 52 through which pressure fluid may flow to the actuating area 47 of the valve 38. Pressure fluid entrapped in the tripper passage 50 5 flows through a passage 53 in the valve chest to act against the actuating area 47 of the valve 39.

The rotation mechanism may be of a well known type comprising a rifle bar 54 which extends through the bushing 36 and interlocks with 10 the piston 23. The rifle bar 54 has a head 55 which carries spring-pressed pawls 56 for engagement with the teeth 57 of a stationary ratchet ring 58 encircling the head 55.

Owing to the arrangement of the ports and 15 passages and the manner in which they are controlled and supplied with pressure fluid, actuating pressure is entrapped in the tripper passages 49 and 50 and when the value of such pressure acting against an actuating area 47 predominates over 20 that acting against the inner end of the valves they will be alternately closed and opened. More specifically, when the piston reaches a position in the piston chamber to close a tripper passage, the pressure fluid flowing into the closed tripper 25 passage acts against the actuating area 47 of the associated valve and causes said valve to move to its closed position, as illustrated in Figure 1 of the drawing.

In the drawing the piston is shown in position 30 to cover the tripper passage 49 during the rearward stroke of the piston. The pressure fluid flowing into said tripper passage then flows through the branch passage 52 and acts against the actuating area 47 of the valve 38 and maintains 35 said valve firmly seated, in closed position, to prevent the flow of pressure fluid from the adjacent channel 35 to the rear inlet passage 44. Meanwhile the valve 39 remains open to admit pressure fluid from the associated channel 35 to 40 the front inlet passage 45 and thus to the front end of the piston chamber to drive the piston rearwardly.

Shortly after covering the free exhaust port 25 the piston covers the tripper passage 50. Pressure fluid is then entrapped in the passage 50 and 45 will act against the actuating area 47 of the valve 39 and cause said valve to be thrown to its closed position before the piston again communicates the front end of the piston chamber with the free 50 exhaust port 25. The piston will then be actuated rearwardly by the expansive action of the pressure fluid in the front end of the piston chamber and when it uncovers the free exhaust port the pressure fluid used for actuating it rearwardly, 55 together with that acting against the actuating area 47 of the valve 38, is exhausted to the atmosphere. The pressure fluid in the channel 35 acting against the actuating area 48 of the valve 38 will then shift this valve to its open position 60 to again admit pressure fluid into the rear end of the cylinder for driving the piston forwardly on its working stroke.

This movement of the valve 38 takes place at 65 the time the piston 23 approaches the rear end of the piston chamber. The piston is then reversed by the pressure fluid flowing into the piston chamber through the rear inlet passage 44 and driven on its working stroke. During this movement of the piston the tripper passage 49 is again covered 70 before the free exhaust port is uncovered and the pressure fluid entrapped in the tripper passage 49 causes the valve 38 to again shift to its closed position. Both valves will remain closed until the rear end of the piston chamber is communicated 75 with the exhaust port 25, whereupon the valve 39

is shifted to its open position by pressure fluid acting against its actuating area 48. Pressure fluid then flows through the front inlet passage 45 to again return the piston.

In rock drills of which the piston has opposed differential pressure areas to which the pressure fluid is valved individually by one of a plurality of identical valves operating at the same stroke it has been found that a considerable saving may be effected in the matter of pressure fluid consumption and that the drill will be better suited for drilling different kinds of rock and at different depths of penetration by selectively controlling the point in the cycle of operation of the piston at which the valve controlling the admission of pressure fluid to the smaller pressure area of the piston is actuated to its closed position. This is particularly true in rock drills in which the piston is actuated throughout a portion of its stroke by expansion of the actuating fluid.

The smaller portion of the piston chamber, in this instance that forwardly of the piston, obviously requires a lesser volume of pressure fluid. Unless the charge to the front end is cut off somewhat earlier during the rearward stroke of the piston, the admission of a given volume of pressure fluid into the front end of the piston chamber might result in discharging fluid directly from supply through the exhaust port without accomplishing useful work, whereas, an equal volume of pressure fluid rearwardly of the piston would merely be sufficient to cause the piston to deliver its normally effective blow against the working implement.

There are, however, instances during the operation of tools of this type when it may be desirable to introduce a heavy charge of pressure fluid into the front end of the piston. For example, when drilling soft rock or deep holes. In such cases it is extremely difficult to effect thorough cleansing of the drill hole. The detritus accumulates around the leading end of the drill steel and retards the movement of the rotation mechanism and consequently reduces the speed of the piston.

In view of the foregoing considerations it is contemplated to enable the action of the valve controlling admission of pressure fluid to the front end of the piston chamber, in this instance the valve designated 39, to be so controlled that its closing movement may be selectively caused to take place early or late during the rearward stroke of the piston 23. The means selected to make such control of the valve 39 possible comprises a manually operable valve 59 disposed rotatably in the rear end of the cylinder 21 and preferably coaxially with the tripper passage 50.

In the front or innermost portion of the valve 59 is a bore 60 which forms a continuation of the tripper passage 50, and a series of radial ports, in this instance two, designated 61 and 62 in the valve 59 afford communication between the bore 60 and the branch passage 53. The ports 61 and 62 lie in the same transverse plane and are so spaced with respect to each other that only one port may register with the branch passage 53 at a time. The ports 61 and 62 are, moreover, of different sizes and increase in capacity in the order designated.

The rear end of the valve 59 contains a spring 63 which seats against the back head 24 to press the valve in the direction of the tripper passage 50, and on the same end of the valve is a lateral lever 64 which extends exteriorly of the cylinder 21 so that it may be conveniently grasped by the operator to shift the valve 59 of the various

controlling positions. Preferably, the rear end of the cylinder is provided with notches 65 and 66 which are so spaced with respect to each other that when the valve 59 occupies a controlling position the lever 64 lies in one of the notches to prevent unauthorized rotation of the valve 59.

When the rock drill is operating under normal drilling conditions and during which the action of the rotation mechanism is not unduly retarded, the control valve 59 occupies a position wherein the port 62 registers with the branch passage 53 so that a comparatively great volume of pressure fluid passes from the tripper passage 50 to the actuating area 47 of the valve 39 within a given period of time. The valve 39 will then be moved to its closed position immediately after the tripper passage 50 is covered by the piston 23 and the latter is then forced rearwardly by the expansive force of the pressure fluid forwardly thereof.

In the event that a collar of detritus forms around the drill steel, thus resisting the action of the rotation mechanism, the valve 59 is shifted to bring the smaller port 61 into registry with the branch passage 53. The introduction of a quantity of pressure fluid into the branch passage 53 sufficient to predominate over that acting against the front end of the valve 39 will thereby be delayed and the valve 39 will, in consequence, remain open for a slightly longer period of time during the rearward travel of the piston. A greater charge of pressure fluid thus passes into the front end of the piston chamber and the shifting of the valve 39 may be delayed until the front end of the piston more nearly approaches the exhaust port 25. In this way a powerful charge of pressure fluid acts against the piston to assure an adequate rotary movement of the working implement against which the piston operates.

I claim:

1. In a fluid actuated rock drill, the combination of a cylinder having a piston chamber and a piston in the piston chamber, means including a valve and passages controlled thereby for distributing pressure fluid to the piston chamber, an actuating area on the valve, a conduit for supplying pressure fluid to the actuating area and being controlled by the piston, and means for selectively varying the rate of flow of pressure fluid to the actuating area to vary the movement of the valve with respect to the movement of the piston.

2. In a fluid actuated rock drill, the combination of a cylinder having a piston chamber and a piston in the piston chamber, means including a valve and passages controlled thereby for distributing pressure fluid to the piston chamber, an actuating area on the valve, a conduit for supplying pressure fluid to the actuating area and being controlled by the piston, and an adjustable valve controlling the passage and having a series of channels of different capacity for varying the rate of admission of pressure fluid to the actuating area.

3. In a fluid actuated rock drill, the combination of a cylinder having a piston chamber and a piston in the piston chamber, means including a valve and passages controlled thereby for distributing pressure fluid to the piston chamber, an actuating area on the valve, a tripper passage controlled by the piston and leading to the actuating area, a leak passage constantly conveying pressure fluid into the tripper passage, a spring-pressed valve in the cylinder rotatable to different positions to control the tripper passage and having a series of channels of different capacity to vary the rate of admission of pressure fluid to the actuating area, and interlocking portions on the spring-pressed valve and the cylinder for holding said valve in placed position.

4. In a fluid actuated rock drill, the combination of a cylinder having a piston chamber and a piston in the piston chamber, a valve chamber, inlet passages leading from the valve chamber to the piston chamber, a pair of valves in the valve chamber to control the inlet passages, each valve having an actuating area, conduits for supplying pressure fluid to the actuating areas and being controlled by the piston, and means for selectively controlling the rate of flow of pressure through one conduit to the associated actuating area.

5. In a fluid actuated rock drill, the combination of a cylinder having a piston chamber and a piston in the piston chamber, a valve chest having a valve chamber coaxial with the piston chamber, a valve for distributing pressure fluid to the piston chamber, an actuating area on the valve, a conduit in the cylinder and the valve chest for supplying pressure fluid to the actuating area, and a manually operable valve in the cylinder having channels of different capacity for varying the rate of flow of pressure fluid through the conduit to the actuating area.

WILLIAM A. SMITH, SR.
